US0D1053126S

(12) **United States Design Patent** (10) Patent No.: **US D1,053,126 S**
(45) Date of Patent: ** Dec. 3, 2024

(54) **COMBINED MULTIFUNCTIONAL PORTABLE CAR JUMP STARTER WITH TIRE INFLATOR AND VACUUM**

FIG. 1 is a top perspective view of a combined multifunctional portable car jump starter with tire inflator and vacuum showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings depict portions of the combined multifunctional portable car jump starter with tire inflator and vacuum that form no part of the claimed design.
